ATTORNEY

UNITED STATES PATENT OFFICE

CHARLES F. MILLER, OF MOORES, PENNSYLVANIA, ASSIGNOR TO WESTINGHOUSE ELECTRIC & MANUFACTURING COMPANY, A CORPORATION OF PENNSYLVANIA

STOKER-GRADE AGITATOR

Application filed November 11, 1926. Serial No. 147,806.

My invention relates to stokers, more particularly to grate agitating mechanism therefor, and has for its object the provision of apparatus of the character designated which shall be simple of design and capable of effective agitation of the grate mechanism over a wide range of operating conditions.

Apparatus embodying features of my invention is illustrated in the accompanying drawings forming a part of this specification, wherein:—

Fig. 1 is a view of the outside of a furnace showing my improved driving means for an over-feed grate section and for the clinker grinding rolls of such furnace; and,

Fig. 2 is a view showing a modification of my invention.

My invention is particularly applicable to the over-feed grate sections of stokers such as is shown and claimed in the application of Donald J. Mossart, Serial Number 147,807, filed November 11, 1926, relating to stokers, and in the application of R. A. Foresman, Serial Number 147,810, filed November 11, 1926, and relating to stokers, both of said applications being assigned to the Westinghouse Electric and Manufacturing Company, though it will be apparent that it is capable of much wider application.

Briefly, my invention comprises a mechanical movement wherein reciprocatory motion is converted to an oscillatory motion through the medium of a toggle mechanism, and is transmitted to the shaft controlling a stoker grate section. A lost motion connection is embodied in the toggle joint and the motion transmitted to the shaft may be varied either by means of an abutment member having a plurality of selective abutment surfaces, and effective for varying the amount of the lost motion in the connection, or by changing the angularity of the toggle, so as to vary its throw or stroke. With either method the degree of movement imparted to the grate section may be readily varied to suit conditions under which the stoker is operating.

Referring now to the drawings for a better understanding of my invention I show, in Fig. 1 in dotted lines as being behind the

furnace wall, a conventional stoker 10 having an oscillatory over-feed grate section 11 adapted to be driven by my improved agitating mechanism. It will be understood that the stoker 10 is of the progressive feed type wherein fuel is admitted at the front and discharged toward the rear over the over-feed grate section 11 and the residue discharged into a clinker pit 12. The clinker pit 12 is provided with suitable clinker grinding rolls 13 which may also be operated coincidentally with the operation of the over-feed grate section 11.

At 16 I show a motor which transmits its motion through a belt 17 to a suitable reduction gear 18. The reduction gear 18 drives a crank shaft 19 to which is connected by means of an arm 14 an actuating rod 21. The actuating rod 21 is provided at its upper end with a slot 22 through which passes a pivot pin 23 of a toggle mechanism. The toggle mechanism is comprised of two links 20 and 25 hinged together by the toggle pin 23. The link 20 is pivoted at 30 to a stationary member suitably secured to the furnace wall, and the link 25 is connected to an arm 24 secured to a shaft 26. The shaft 26 supports the over-feed grate section 11 and is adapted to be oscillated in order to impart an agitating movement to the over-feed grate section. As the shaft 19 rotates, the toggle mechanism is raised and lowered imparting an oscillatory motion to the shaft 26.

In order to vary the oscillation of the shaft 26, or the range of movement imparted to the pivot pin 23, I provide an abutment member 27 having a plurality of selective abutment surfaces 28—28 provided along its side. The abutment member 27 is pivoted to the rod 21 at 29 so that it may be moved about said pivot point to bring any one of the abutment surfaces into position for engagement with the toggle pin 23, each of the abutment surfaces being effective to provide a different length stroke to the toggle mechanism.

In order to select the abutment surface required for the desired travel, I provide a rod 31 pivoted to the abutment member 27 at 32 and effective for moving said abutment member around the pivot 29. The rod 31 is oper-

ated by means of a handle 35 the handle 35 being resiliently connected to the rod 31 by means of two springs 33 and 34 and slidingly connected to the upper end of the rod 21. Holes 36 are formed in the upper end of the rod 21 in properly spaced relation so that whenever the handle 35 is raised or lowered and a pin 37 inserted therein and through one of the holes 36, the rod 31 is moved to such a position that one of the abutment surfaces 28 falls directly beneath the toggle pin 23.

Should the handle 35 be moved at a time when an abutment surface 28 of the cam member 27 is in engagement with the toggle pin 23 the springs 33 and 34 permit movement of said handle 35 relative to the rod 21 so that it may be moved and engaged with the desired hole 36 without affecting the abutment member 27 until it becomes disengaged from the toggle pin 23 by reason of the lost motion connection formed by the upper end of the slot 22.

It will be seen that, with the apparatus just described, the amount of movement of the over-feed grate section can be controlled within desired limits to accommodate fuel of different characteristics. For example, if a fuel having a high clinker forming content is being employed in the stoker, the over-feed grate section would be agitated to the full extent of movement procurable in order to break up the forming clinkers, whereas, if a fuel of lower clinker forming content is employed only a medium or relatively small latitude of movement is required.

It may furthermore be desirable to operate the over-feed section in conjunction with the clinker grinder rolls of the clinker pit. I accordingly show, in Fig. 1, the clinker grinder rolls 13 connected to the crank shaft 19 through an arm 40 secured to the shaft 19, a connecting link 41 and through a loosely mounted arm 42 depending from the shaft of one of the rolls 13. As the crank shaft 19 is rotated the arm 42 is swung back and forth and transmits its motion to the roll 13 with which it is connected through a pawl and ratchet mechanism. The arm 42 is provided with an integral extension 48 which projects beyond one of the clinker rolls and is provided with a pivoted pawl member 43 which engages a ratchet wheel 49 keyed to the clinker roll. A rod 44 connects the arm 48 with an arm 46 of the other roll 13 so that motion from the first mentioned roll 13 is transmitted to the other roll and turns said roll through a pawl 47 engaging a ratchet wheel 50. Thus the clinker grinder rolls 13 are operated in synchronism with the over-feed grate section 11. The actions of the rolls and of the grate section may thus be coordinated to suit varying conditions of volume of refuse to be handled.

Referring now to Fig. 2, I show a modified form of my improved drive. The principal

parts of this drive, such as the motor, reduction gear and connecting rods may be the same as described in connection with Fig. 1 and require no further detailed description. The principal difference between the two forms of drive resides in the arrangement of the toggle mechanism. In accordance with this form of my invention the toggle mechanism comprises a pin 51 and two links 52 and 53. The link 53 is connected to an arm 24^a secured to a shaft 26^a as in the previously described modification. The link 52 is carried by a movable abutment 54. The abutment 54 may be moved away from or toward an operating rod 21^a as by means of a screw and nut connection 56—57. The pin 51 rides in a slot 22^a of the rod 21^a as in the previously described modification. The abutment 54 is placed in such a position with respect to the connection between the link 53 and the arm 24^a that, as the shaft 19 rotates, the rod 21^a carries the toggle pin 51 upwardly or downwardly beyond a line drawn from the abutment 54 to said connection.

In this manner, when the shaft 26^a is oscillated, together with the over-feed grate section, said over-feed grate section is raised until the links 52 and 53 are just beyond the straight line position, and the over-feed grate section then falls by gravity to its lower position. With this form of drive, the over-feed grate section, when pushed upwardly into the fire does not remain long in its upper position where it would be liable to be burned by contact with the fire, but drops quickly backward to its lower, cooler position. Furthermore, the slot 22^a is arranged so that the rod 21^a transmits motion to the shaft 26^a both as it moves upwardly and downwardly. Thus the shaft 26^a is given a double oscillatory movement for each revolution of the crank shaft 19. In order to vary the latitude of motion imparted to the shaft 26^a, the abutment 54 may be moved away from or toward the rod 21^a.

From the foregoing it will be apparent that I have devised an improved mechanism for agitating a stoker grate, simple of design, dependable in operation and capable of adjustment over a wide range to compensate for varying operating conditions.

While I have shown my invention in two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. In a stoker, the combination of an over-feed grate section; means for pivotally supporting the grate section; and means for imparting an oscillatory movement to the grate

section about its pivotal support; said motion imparting means including an operating rod having a longitudinal slot, means for imparting a reciprocatory motion to the rod, toggle mechanism having one link pivotally secured at its outer end to a stationary part and a second link operatively connected at its outer end to the grate section, an actuating pin connecting the inner ends of the toggle links and slidably disposed within the slot, and means including an abutment member for engaging the pin, said abutment member having selective abutment surfaces for varying the effective length of the slot.

2. In a stoker, the combination of a grate section; means for supporting the grate section to permit movement of such section; and means for moving the grate section; said moving means including a rod having a slot, means for imparting a reciprocatory motion to the rod, toggle mechanism operatively connected to the grate section and having an actuating pin slidably disposed within the slot, and means for varying the throw of the toggle mechanism.

3. In a stoker, the combination of a grate section; means for supporting the grate section to permit movement of such section; and means for moving the grate section; said moving means including an operating rod having a longitudinal slot, means for imparting a reciprocatory motion to the rod, toggle mechanism operatively connected to the grate section and including an actuating pin slidably disposed within the slot, and an abutment member secured to the rod and engaging the actuating pin for operating the same, said abutment member having a plurality of selective abutment faces for engaging the pin and effective when moved to different positions to vary the effective length of the slot.

4. In a stoker, the combination of a grate section; means for pivotally supporting the grate section; and means for moving the grate section about its pivotal support; said moving means including a rod having a longitudinal slot, means for imparting a reciprocatory motion to the rod, toggle mechanism operatively connected to the grate section and including an actuating pin slidably disposed within the slot, an abutment member rotatably mounted on the rod adjacent to the slot and having a plurality of selective abutment surfaces for engaging the pin, each surface being effective to provide a different effective length for the slot, and means for rotating the abutment member.

5. In a stoker, the combination of a grate section; means for pivotally supporting the grate section; and means for moving the grate section about its pivotal support; said moving means including a rod having a longitudinal slot, means for imparting a reciprocatory motion to the rod, toggle mechanism operatively connected to the grate section and

including an actuating pin slidably disposed within the slot, an abutment member rotatably mounted on the rod adjacent the slot and having a plurality of selective abutment surfaces for engaging the pin, each surface being effective to provide a different effective length for the slot, an operating arm for the abutment member, means connected to the rod for moving the operating arm to different desired positions, and resilient means connecting the last mentioned moving means and the operating arm.

6. In a stoker, the combination of a grate section; means for pivotally supporting the grate section; and means for moving the grate section about its pivotal support; said moving means including a rod having a longitudinal slot, means for imparting a reciprocatory motion to the rod, toggle mechanism operatively connected to the grate section and including an actuating pin slidably disposed within the slot, an abutment member rotatably mounted on the rod adjacent the slot and having a plurality of selective abutment surfaces for engaging the pin, each surface being effective to provide a different effective length for the slot, an operating arm for the abutment member, movable means connected to the rod, selective means for positioning the last mentioned movable means on the rod in different positions corresponding to different positions of the abutment member, and resilient means connecting the last mentioned movable means and the operating arm of the abutment member.

In testimony whereof, I have hereunto subscribed my name this third day of November, 1926.

CHARLES F. MILLER.
